MOTOR-CONTROLLER.

1,108,905.

Specification of Letters Patent.

Patented Sept. 1, 1914.

Application filed April 23, 1909. Serial No. 491,870.

To all whom it may concern:

Be it known that I, CLARK T. HENDERSON, a citizen of the United States, residing at Milwaukee, in the county of Milwaukee and State of Wisconsin, have invented new and useful Improvements in Motor-Controllers, of which the following is a full, clear, concise, and exact description, reference being had to the accompanying drawing, forming 10 a part of this specification.

My invention relates to controllers for electric motors, and more particularly to controllers adapted to automatically accelerate the motor. In controllers of this type, 15 it is advantageous to provide one or more throttling devices to check the removal of the starting resistance from the motor circuit upon the occurrence of abnormal conditions. While such throttling devices 20 check the removal of the starting resistance from circuit upon an excessive flow of current, yet they in no wise retard the acceleration of the motor unless abnormal conditions do occur during the starting period. 25 Hence, if the load is very light, the throttling devices are not likely to respond, and consequently the motor is brought up to normal speed in a very short time. To bring the motor up to speed in the shortest 30 possible time is very advantageous in many instances. In some instances, however, as in elevator service, too rapid acceleration of the motor, even though without danger of injuring the motor, is objectionable in 35 that it starts the car with more or less of a jerk, thereby causing discomfiture of the passengers. Of course, where the load is heavy, there is very little likelihood of the motor accelerating so rapidly as to jerk the 40 car in starting, but where the load is very light, this often occurs.

It is, therefore, the object of my invention to provide means, in addition to the throttling devices heretofore mentioned, 45 which will insure at least a predetermined lapse of time before the motor is brought up to full speed, regardless of its load.

I further provide means whereby the minimum length of time required to bring 50 the motor up to normal speed may be varied as desired.

For the purpose of more fully disclosing the characteristic features of my invention,

I shall describe the embodiment thereof illustrated in the accompanying drawing.

Of course, my invention is susceptible of 55 various modifications, the system shown in the drawing merely serving to illustrate one form thereof.

The system of control, which I have shown, includes a main switch 1; resistance 60 switches 2, 3 and 4; throttling switches 5, 6 and 7, and a relay device 8. The main switch 1 is provided with an operating winding 1^a and the resistance switches 2, 3 and 4, with operating windings 2^a, 3^a and 65 4^a, respectively. The throttling devices 5, 6 and 7 are provided with controlling windings 5^a, 6^a and 7^a, respectively. The resistance switches 2, 3 and 4 are arranged to control resistances R², R³ and R⁴, arranged in the 70 circuit of the motor which, as shown, is provided with an armature A and a field winding F. The plunger of the operating winding of the main switch 1 carries a pair of contact disks 9 and 9^a, each adapted to 75 engage a pair of stationary contacts. The plungers of the operating windings 2^a and 3^a of the resistance switches 2 and 3 each carry a similar pair of contact disks 10, 10^a, 11 and 11^a respectively. The plunger 80 of the winding 4^a carries a single contact disk 12, adapted to engage a pair of stationary contacts. The relay 8 comprises a solenoid, having a winding 13 and a core 14, which carries contact disks 15 and 16. 85 The contact disk 15 is adapted, when in one position, to engage a pair of contacts 17, and when in another position to engage a pair of contacts 18. The contact disk 16 is adapted to engage a pair of contacts 19. 90 The contacts 17 are bridged by a resistance r¹, while the contacts 18 are bridged by a resistance r². The contacts 19 are bridged by a resistance r⁴. The tail rod 95 of the core 14 of the winding 13 is connected to the plunger of a double acting dash-pot 20, which, of course, retards the movement of the core 14 in both directions. This dash-pot may be of any preferred form, and may advantageously be provided 100 with some means of adjustment for the purpose hereinafter set forth. Current is supplied to the motor and to the various windings from main lines 30 and 31 through a double pole switch 32. Another switch 105

27, adapted to engage contacts 28 and 29, is provided for the purpose hereinafter set forth.

I shall now describe the operation of the controller.

Upon closure of the switch 32 circuit is closed by conductors 33 and 34, through auxiliary contact 9^a of the main switch 1 by conductor 35 through the operating winding of the relay 8 by conductors 36 and 37 through the auxiliary contact 11^a of the resistance switch 3 by conductors 38 and 39 to the negative side of the main line. This causes the energization of the winding 1^a of the relay 8, which draws up its plunger, thereby moving the contacts 15 and 16 into the position illustrated. Closure of the switch 27 completes the circuit of the operating winding of the main switch 1 from conductor 33 through said winding by conductor 40 through the auxiliary contact 10^a of the resistance switch 2 by conductor 41 through the auxiliary contact 12 of the switch 4 by conductors 37, 38 and 39, to the negative side of the main line. The winding 1^a being energized, closes the main switch 1, which closes the motor circuit from conductor 33 through switch 1 by conductor 42 through the winding of the throttle switch 5 and through the resistances R², R³ and R⁴ by conductor 43 through the motor armature A and series field winding F by conductor 44 to the negative line. Thus the motor is started with all the resistance in circuit. Upon closure of the main switch 1, the contact disk 9 is moved into engagement with its stationary contacts. This completes a circuit from switch 27 by conductor 45 through contact disk 9, throttle switch 5, conductor 46, through the winding 2^a by conductor 47 through resistance r² by conductor 48 to the negative line. Owing to the inclusion of the resistance r² in the circuit of the winding 2^a, said winding is not sufficiently energized to close the switch 2. However, when the auxiliary contact 9 of the main switch engages its contacts, the auxiliary switch 9^a is disengaged from its contacts, which results in opening the circuit of the winding 13 of the relay device 8. Hence, the plunger 14 of the relay device is permitted to descend against the action of the dash-pot 20. After a predetermined interval, according to the adjustment of the dash-pot 20, the contact 15 will engage the contacts 18, thereby short circuiting the resistance r² in circuit with the winding 2^a. Thereupon said winding will become fully energized, assuming that the throttle switch 5 is in normal position. As soon as the winding 2^a is fully energized, it closes the switch 2, which removes the resistance R² from the motor circuit. Should, however, the throttle switch 5 be opened before the switch 2 is closed, said switch 2 cannot be

closed until after normal conditions are restored and the throttle switch 5 returns to normal position, owing to the fact that in open position the throttle switch 5 interrupts the circuit of the winding 2^a. It will be seen, however, that with this arrangement at least a predetermined lapse of time is insured between the closure of the main switch 1 and the resistance switch 2, regardless of whether or not the throttle device has in the meantime responded. Of course, the operation of the throttle switch 5 may prolong the interval between the closure of the main switch and the first resistance switch. In such an event, the relay device will have time to operate before the throttling switch returns to normal position, and, hence, it will not further retard the operation of the accelerating switch. Upon closure of the switch 2, the circuit of the winding 1^a of the main switch is interrupted at the contact disk 10^a, thereby inserting a resistance 49 in circuit with the winding 1^a. This establishes a high resistance maintaining circuit for the main switch, which may be traced from conductor 40 through resistance 49 to conductor 39. Also upon closure of the switch 2, circuit is again closed through the operating winding 13 of the relay device 8, and also through the operating winding 3^a of the switch 3. The latter circuit may be traced from conductor 46 through the auxiliary contact 10 of the switch 2 through the throttle switch 6 by conductor 50 through said winding 3^a by conductor 51, through the resistance r³ and conductor 48 to the negative line. Owing to the inclusion of the resistance r³ in this circuit, said winding will not be sufficiently energized to close the switch 3. However, as before stated, circuit is at this time closed through the winding 13 of the relay device 8, and may be traced from conductor 46, across contact disk 10 by conductor 52 to conductor 35 through the winding 13 and thence back to the negative line, as already set forth. The plunger of the relay 8 is thereby raised against the action of the dash-pot 20, and after a predetermined interval of time, according to the adjustment of the dash-pot, the contact 15 will bridge the contacts 17, thereby removing the resistance r³ from the circuit of the winding 3^a. The winding 3^a will then respond and close the switch 3, assuming that the throttle switch 6 is closed. Closure of the switch 3 removes the resistance R³ from the motor circuit. Should the throttling device 6 respond to an excessive flow of current before the switch 3 is closed, the interval between the closure of the switches 2 and 3 might be prolonged, but at any rate, a predetermined lapse of time between the closure of the switches is insured by the relay 8. Upon closure of the switch 3, circuit is closed from

conductor 50 through contact disk 11 of the switch 3 and throttle switch 7 by conductor 53 through winding 4¹ by conductor 54 through resistance r^4 , and by conductor 48 to the negative side of the main line. The switch 4 cannot immediately close, owing to the inclusion of the resistance r^4 in the circuit of its operating winding. However, upon closure of the switch 3, the circuit of 5 the winding 13 of the relay 8 is opened at contact disk 11^a, which permits the contact 16 of the relay to descend against the action of the dash-pot 20. The contact 16 then short circuits the resistance r^4 , thereby permitting 10 the switch 4 to close unless prevented by the throttle switch 7. Here, again, it will be seen that at least a predetermined lapse of time is insured between the closure 15 of the switches 3 and 4. As the switches 2, 3 and 4 close successively, they gradually remove the resistances R^2 , R^3 and R^4 from circuit, thereby gradually accelerating the motor. Closure of these switches also results 20 in short circuiting their corresponding throttling devices, thereby rendering the same ineffective to cause said switches to open after they have once been closed. Upon closure of the switch 4, the contact disk 12 is disengaged from its contacts. Here it 25 should be noted that the energizing circuit of the winding of the main switch is completed through the contact disks 10^a, 11^a and 12 of the resistance switches. Hence, when any of these contact disks are actuated by 30 the closure of their respective resistance switches, the resistance 49 is inserted in circuit with the winding of the main switch. The resistance 49 being proportioned to reduce the flow of current through said winding 35 to an amount just sufficient to maintain the main switch closed, but insufficient to close the same, it will be seen that when the main switch is once opened, it cannot be again closed until all of the resistance 40 switches open to return the contact disks to initial position.

With the arrangement set forth, it will be seen that I provide for at least a definite lapse of time between the closure of successive accelerating switches, even though the throttling devices do not respond during the entire starting period. As before set forth, if the throttling switches respond during the starting period, they in no 50 wise affect the operation of the relay device. Hence, if the throttling switches prolong the intervals between the closure of successive accelerating switches, said accelerating switches will operate immediately upon 55 the return of the throttling switches to initial position. Furthermore, it will be seen that by adjusting the dash-pot of the relay device, the minimum lapse of time between the closure of successive switches 60 may be varied as desired, thereby insuring

any minimum lapse of time before the motor is brought to normal speed.

Of course, my invention is not limited to any particular form of relay device, nor is it limited to any particular form of controller. 70

Having thus described my invention, what I claim as new and desire to secure by Letters Patent, is—

1. In a controller for electric motors, in combination, a plurality of successively operated switches having individual operating means and a single automatic device for controlling said switches to insure a predetermined lapse of time between the operation of successive switches, said device being controlled by said switches to operate irrespective of the motor current. 75

2. In a controller for electric motors, in combination, a plurality of switches, a plurality of electromagnetic windings for operating said switches successively, and a single automatic device controlling said windings to insure a predetermined lapse of time between the operation of successive 80 switches, said device being controlled by said switches to operate independently of current conditions of the motor circuit. 85

3. In a controller for electric motors in combination means for accelerating the motor by steps and means controlled exclusively by said first mentioned means and operating independently of current conditions in the motor circuit for insuring a definite time interval between successive steps 90 of acceleration. 95

4. In combination, means for accelerating the motor by steps, means controlled by said first mentioned means for insuring a definite time interval between successive steps 105 of acceleration and means independent of said second mentioned means for arresting the operation of said first mentioned means while abnormal conditions prevail in a motor circuit. 110

5. In a motor controller for electric motors, in combination, a plurality of electro-responsive switches and automatic means electrically controlled directly by said switches and operating independently of the 115 current conditions of the motor circuit for preventing the response of each of said switches until a preceding switch has responded and said means has been operated, thereby insuring a definite interval between 120 the closure of successive switches.

6. In a controller for electric motors, in combination, a plurality of switches, a plurality of successively energized windings for operating said switches, a separate resistance in circuit with each of said windings for rendering the same ineffective to close its corresponding switch, and automatic means controlled by said switches for removing the resistance in circuit with the wind- 130

ing of each switch upon the lapse of a predetermined time after the operation of a preceding switch.

7. In a controller for electric motors, in combination, a plurality of switches, a plurality of successively energized windings for operating said switches, a resistance in circuit with each of said windings for rendering the same ineffective to close its corresponding switch and an electroresponsive device alternately energized and deenergized, depending upon the operation of said switches, for removing the resistance in circuit with the winding of each switch upon the lapse of a predetermined time after the operation of a preceding switch.

8. In a controller for electric motors, in combination, a plurality of electromagnetic resistance switches arranged to operate successively, a plurality of mechanically connected relay switches each arranged to control the operating winding of one of said resistance switches, each of said relay switches tending to move automatically to cause the energization of its corresponding winding upon the operation of one of said resistance switches and means for retarding the operation of each of said relay switches for a predetermined time.

9. In a controller for electric motors, in combination, a plurality of electromagnetic resistance switches arranged to operate successively, a plurality of relay switches, each arranged to control the operating winding of one of said resistance switches, said relay switches being arranged to move together and to move alternately in opposite directions to cause the energization of the operating windings of said resistance switches, means for retarding the operation of said relay switches for a predetermined time, when the same move in either direction, and an electromagnet for moving said relay switches in one direction, said electromagnet being arranged to be alternately energized and deenergized as said resistance switches successively operate.

10. In a controller for electric motors, in combination, a plurality of successively actuated switches, means for checking the successive operation of said switches upon the occurrence of abnormal conditions in the motor circuit and an automatic time relay controlled by said switches and independent of said means for insuring a definite time

interval between the operation of successive switches.

11. In a controller for electric motors, in combination, a plurality of successively actuated switches, means for checking the successive operation of said switches upon the occurrence of abnormal conditions in the motor circuit and an automatic time relay controlled by said switches for insuring a definite time interval between the operation of successive switches.

12. In a motor controller, in combination, a plurality of electromagnetic switches arranged to operate successively, a controlling switch for the operating winding of each of said resistance switches, each of said controlling switches being adapted to automatically operate upon the closure of one of said resistance switches to cause the energization of the winding of its corresponding resistance switch, means for retarding the operation of each of said controlling switches for a predetermined time, and an electroresponsive throttling switch in circuit with the operating winding of each of said resistance switches for further checking the successive operation of said resistance switches upon the occurrence of abnormal conditions.

13. In a controller for electric motors, in combination, a plurality of electromagnetic resistance switches, each of said switches when closed being adapted to complete the circuit of the operating winding of the next succeeding switch, an automatic controlling switch in circuit with the operating winding of each resistance switch, said controlling switches being arranged to insure the lapse of a predetermined time between the closure of successive resistance switches, and an electroresponsive throttling switch in circuit with the operating winding of each resistance switch, said throttling switches being adapted to check the successive operation of said resistance switches upon the occurrence of abnormal conditions.

In witness whereof, I have hereunto subscribed my name in the presence of two witnesses.

CLARK T. HENDERSON.
